FOOT PROTECTOR

Minnie Levy, Brooklyn, N. Y., assignor of one-half to William Levy, Brooklyn, N. Y.

Application February 13, 1939, Serial No. 256,209

3 Claims. (Cl. 36—10)

This invention relates to foot appliances or protectors, and more particularly to a device for protecting the toe area and forward portion of the foot against contact with the shoe, or other bodies external of the protector, or against contact with external disease germs and especially against contact with the tinea trichophyton parasite commonly known as the germ of athlete's foot.

Under modern living conditions there exists a progressively increasing number of cases of foot infection commonly known as athlete's foot. This infection is usually confined to the toe area and forward portion of the foot and is highly contagious. Unless some provision is made to protect this portion of an infected foot, the agitation resulting from this infection induces the tendency of the infected person to scratch the foot, which, in turn, aggravates the infection and tends to spread it to other portions of the foot. This, of course, prolongs the period of the infection, and also tends to further spread the disease. This infection is usually contracted through the common use of public showers, bath houses, bathing beaches and pools, gymnasiums and club facilities. Another prolific source for the contraction of the disease resides in the mode of selling new shoes. In all instances, where the disease has been contracted, it is thought that the period of infection could be greatly shortened and prevention of further spreading of the disease be brought about by properly protecting the infected foot.

It is an object of this invention, therefore, to provide a foot protector which is capable of readily conforming to the affected part of the foot, thereby preventing the contact of the infected portion of the foot with external bodies, or the contact of external disease germs with the protected portion of the foot.

Another object of this invention is to provide a foot protector of relatively thin elastic non-porous material which is shaped to readily conform to and encase the toe area and forward portion of the foot to thereby protect this portion of the foot against contact with external bodies, or against the contact of external disease germs with the protected portion of the foot.

Another object of the invention is to provide a foot protector of relatively thin elastic non-porous material which is shaped to conform to and encase the toe area and forward portion of the foot and which protector includes means for securing the protector to the foot or to a stocking or sock worn on the foot.

Another object of this invention is to provide a foot protector formed of relatively thin elastic material, which protector may be secured within a shoe to protect the foot against contact with the shoe, and the protector incorporates means for maintaining the protector in foot receiving configuration within the shoe.

It is also an object of this invention to provide a foot protector of generally improved construction, whereby the device will be simple, durable and inexpensive in construction, as well as convenient, practical and efficient in its use.

With the foregoing and other objects in view which will appear as the description proceeds, the invention resides in the combination and arrangement of parts and in the details of construction hereinafter described and claimed, it being understood that various changes in the form, proportion and details of construction may be made within the scope of the claims without departing from the spirit or sacrificing any advantages of the invention.

For a more complete disclosure of the invention, a detailed description of the foot protector will now be given in connection with the accompanying drawings forming a part of the specification, wherein:

Figure 1 is a perspective view of a preferred form of the foot protector.

Figure 2 is a bottom plan view thereof, a portion being broken away.

Figure 3 is a top plan view of the foot protector.

Figure 4 is a transverse sectional view taken on the line 4—4 of Figure 3.

Figure 5 is an enlarged fragmental detailed sectional view taken on the line 5—5 of Figure 3.

Figure 6 is a similar view taken through a slightly modified arrangement.

Figure 7 is a perspective view of another preferred form of foot protector.

Figure 8 is a perspective view of a slightly modified form of the invention.

Figure 9 is a perspective view of a further modified form of the foot protector, and

Figure 10 is a perspective view of a form of the foot protector in which a reinforced portion is employed to secure the protector on the foot.

Referring to the drawings in which similar reference characters designate corresponding parts, there is depicted, in Figures 1 to 5, a form of invention which includes a relatively thin elastic non-porous body portion 10 which is preferably shaped to conform to the toe area and forward portion of the wearer's foot. The front or toe

portion 11 of the non-porous body member is closed to thereby protect the toe area of the foot against contact with any body external of the protector. The rear portion of the body member 10 is open, as indicated at 12, for the reception of the forward portion of the foot and to facilitate the entrance of the foot into the protector body 10. The top portion of the body is cut inwardly towards the forward or toe portion of the body, as indicated at 15, in order that the foot may be more readily positioned within the protector 10.

This form of protector is adapted to be secured within shoes, so that when a customer tries on a new pair of shoes in a store, the customer's foot will not contact with the toe area or forward portion of the shoe. This arrangement has double advantage, inasmuch as it protects the customer who is trying the shoe on against disease germs that may have been deposited therein by a former user, and also protects the shoe against infection in the event the customer may suffer from an infected foot. In order to maintain the protector body 10 in foot receiving position and configuration within the forward or toe portion of the shoe, not shown, each protector is provided with a bottom or sole stiffening or securing member 16 preferably formed of any suitable non-elastic material such as leather, paper, fiber or any suitable composition. The forward portion of the stiffening or securing member 16 is shaped to conform to the lower forward portion of a foot, as indicated at 17, and this portion is preferably secured to the body 10 by adhesive or any other suitable securing material. The forward portion 17 of the securing member 16 may be secured to either the inside or the outside of the protector 10, but a preferable arrangement is one in which the forward portion 17 is secured within the body member 10 to form the sole portion thereof. Again, this forward sole portion 17 of the securing member 16 may be shaped to conform to either the right or left foot, in instances where shoes are sold in pairs of right or left, or a common shape may be employed to fit either the right or left foot. Inasmuch as the forward or sole portion 17 of the stiffening and securing member 16 is shaped to conform to the bottom or sole of the forward portion of the foot, it is manifest that this arrangement will hold the bottom or sole portion of the protector 10 in foot receiving shape or configuration. A securing tab 18 extends rearwardly from the sole portion 17 of the stiffening and securing member 16, and it is preferably shaped to conform to the heel portion of the foot. At the rear or heel terminal of the securing tab 18, a layer of suitable adhesive 19 is deposited preferably on the outer or bottom surface thereof, and this, in turn, is temporarily covered by a protecting strip 20 of fabric or other suitable material. The forward terminal of the protector strip 20 projects forwardly beyond the area of the adhesive 19 to provide a grasping ear 21, so that the user may grasp the ear 21 in the fingers and strip the protecting strip from the adhesive 19, thus exposing the adhesive 19 so that it may engage the bottom of the shoe to secure the securing strip 16 thereto. Additional side and top stiffening and securing members 22 are provided, and the forward or toe portion 23 of each member 22 is secured to the body 10 of the protector and preferably therein, although it is to be understood that it may be secured to the exterior of the body 10, if pre-

ferred. The forward or toe portion 23 of each stiffening and securing member 22 is so shaped that the stiffening members maintain the top and side portions of the protector body 10 in foot receiving shape or configuration. Each securing member 22 has a securing tab 25 which extends rearwardly from the protector body 10, and has a layer of adhesive 26 preferably deposited on its outer rear terminal. This adhesive 26 is also covered by a protecting strip 27 having a grasping or manipulating ear 28, and this protecting strip is stripped from the adhesive 26 in the manner hereinbefore disclosed. In order to aid in correctly positioning the protector 10 within the shoe, a line or other indicating indicia 30 is preferably inscribed or formed on the top portion of the protector body 30 to indicate the longitudinal center of the top portion of the protector.

In positioning the protector 10 within the toe portion of the shoe, line 30 indicates the longitudinal center of the top portion of the protector, and this line is located within the shoe as near as possible to the longitudinal center of the toe portion of the shoe. The protector strips 20 and 27 are then stripped from the securing tabs 18 and 22 so that the adhesive thereon may be exposed and then pressed against the inside of the shoe to secure the protector within the toe portion of the shoe. Now the foot may be readily inserted in the shoe to determine if the size is correct, and after the shoe has been "tried on," the foot may be readily withdrawn without drawing the protector from the shoe. Thus it is seen from this arrangement, that if a person affected with athlete's foot or other contagious foot disease tries on the protected shoe, the infected part of the foot can not engage the shoe, and since the protector closely conforms to the inner part of the shoe, it does not inconvenience the customer in any way in trying on the shoe. This arrangement affords a two fold protection, because if the shoes have been previously tried on and they had not been protected by a similar protector, the use of the device now serves for protecting the present user against previously deposited infectious germs, and the use of the protector in the present instance will also protect any subsequent user of the shoe against any infectious germs that may be present on the foot of the present user if said protector is removed at the end of the present user's use. A protector of this type is of peculiar advantage in trying on shoes in a store, or in trying on shoes that have been forwarded through the mail by the usual mail order houses. In such instances, the protector is inserted in the shoe before it is mailed to the customer, and, if, for any reason, the shoe is returned to the store, the protector is removed and a fresh one inserted, thus protecting the subsequent purchaser of the shoe against any disease germs.

In the form of the invention disclosed in Figure 6, a strip of adhesive 32 is carried by a securing tab 33 without a protecting strip thereover, and this adhesive is preferably of such character that it will readily adhere to the stocking, sock or interior of the shoe without leaving a deposit thereon.

In Figure 7 there is disclosed a form of the invention which includes a relatively thin elastic non-porous body 35 which is closed at its toe portion, as indicated at 36, and open at its rear portion. An upper V-shaped securing tab 37 extends rearwardly from the upper toe portion of

the protector body 35, and at its rear terminal this tab carries on its inner face a thin strip or film of adhesive 38 which is, in turn, covered by a fabric protector strip 39 having a gripping ear 41 extending forwardly therefrom. A lower or 5 rear-sole V-shaped securing tab 42 extends rearwardly from the lower sole portion of the protector body 35, and the rear or heel portion of the sole securing tab 42 is provided with a film of adhesive 43 and a protector strip 45 similar to the arrangements hereinbefore described. This entire protector is formed of relatively thin elastic non-porous material, such as rubber, gum or suitable composition, and it may be readily applied to the foot of the user by drawing it over the toe area and forward portion of the foot by simply grasping the rear terminals of the securing tabs 37 and 42, or, if preferred, the protector may be rolled onto the foot. In order to aid in correctly positioning the protector on the user's foot, an indicating line or mark 46 may be inscribed or formed on the upper portion of the protector body 35 and the upper surface of the securing tab 37 to indicate the longitudinal center 10 of these members. After the protector has been positioned on the foot, the fabric protector strips 39 and 45 are stripped from the adhesive 38 and 43, and the adhesive is then pressed against the stocking or sock of the user to thus secure the protector on the foot. This form of protector may be advantageously employed in shoe stores to protect the user against infection of previously tried on shoes, or to protect subsequent users against any infectious germs that may be present on the foot of the present user, and, inasmuch as the entire protector is formed of relatively thin elastic non-porous material, it readily conforms to the shape of the wearer's foot so that it does not interfere in any way in trying on the shoes.

In Figure 8 a slightly modified form of the invention is disclosed, and this arrangement is similar to that depicted in Figure 7 except that V-shaped securing tabs 47 extend rearwardly from the side portions of the protector body 48 instead of from the top and bottom, as in the form disclosed in Figure 7. Otherwise this protector is constructed and is positioned on the foot in a manner similar to that disclosed in Figure 7, except that the adhesive strips 50 and 51 carried by the rear terminals of the securing tabs 47 are pressed against the side portions of the stockinginged foot rather than against the sole and top portion thereof.

Another form of the invention is disclosed in Figure 9, and this form is similar to the arrangement disclosed in Figure 8 except that an endless securing band 52 extends rearwardly from the side portions of the protector body 53. This protector is also formed of relatively thin elastic non-porous material which readily conforms to the configuration of the user's foot, and it is securely held to the foot by simply stretching the securing band 52 over the heel portion of the foot so that it engages the heel portion and prevents the body portion 53 from slipping from the toe area and forward portion of the user's foot.

This form of the invention may also be advantageously used in trying on shoes in the stores, or it may be worn as a protection against infectious disease germs while bathing or while engaged in any preferred form of athletic endeavor, such as running or gymnasium work, or, it may also be worn as a protector while sleep-

ing to prevent the contact of the user's foot with any extraneous object.

In Figure 10 there is disclosed a form of the invention which includes a relatively thin elastic non-porous body 55 which is shaped to conform to the toe area and forward portion of the foot. The toe portion of the body 55 is closed, as indicated at 56, and its rear portion is open, as indicated at 57. In order to aid in securing the body 55 on the user's foot, a band or strip 58 of increased thickness extends around the rear terminal of the body 55 and this band is interrupted at its upper portion by an inwardly extending opening 60. In this form of the invention a line or other suitable mark 61 is inscribed or formed on the top portion of the body 55 to indicate the longitudinal center of the body to thereby aid in correctly positioning the protector on the foot. The body 55 may be readily positioned on the foot by simply rolling it thereon until it is correctly positioned over the toe area and forward portion of the foot. The resilient characteristic of the material tends to secure the body 55 on the toe area and forward portions of the foot, and the reinforced band or strip 58 clings to the intermediate portion of the foot, to thus insure that the protector will remain securely upon the foot. This form of protector may be placed upon the bare foot as a protection against contact with external disease germs when the user is bathing, swimming, or engaged in any preferred athletic endeavor, hereinbefore mentioned. This form of protector, in common with other forms, may also be worn upon the beach to protect the wearer's foot against sand and disease germs, or it may be worn as a protection while sleeping, as hereinbefore pointed out.

From the foregoing it is manifest that applicant has, in the various forms of the invention disclosed, provided a convenient, highly efficient and commercially acceptable device to protect the wearer against contact with the infectious disease germs when trying on shoes in a store or shoes received from mail order houses. Furthermore, it may be worn as a protector while sleeping, as stated, or when engaged in any preferred athletic endeavor, above mentioned, or while bathing, swimming, or walking on the beach or walking from the club house to and from the field of athletic endeavor. Again, the elastic non-porous character of the material employed enhances the efficiency because it permits the protector to readily conform to the configuration of the wearer's foot and its non-porous character prevents external disease germs from contact with the foot and also prevents an infected foot from contacting with any body external of the protector.

Having thus described my invention, what I claim as new and useful is:

1. A foot protector comprising a body of thin elastic non-porous material having a sole portion and an upper portion shaped to substantially conform to and incase the toe area and forward portion of the foot, a plurality of non-elastic stiffening members secured to the body to embrace substantially the entire upper portion of the body to thereby maintain the body in foot-receiving configuration, the stiffening members having guiding and securing tabs extending rearwardly from the body and terminating at locations within the length of the sole, and means for securing the said tabs to the shoe.

2. A foot protector comprising a body of thin elastic non-porous material having a sole por-

tion and an upper portion shaped to substantially conform to and incase the toe area and forward portion of the foot, a plurality of non-elastic stiffening members secured to the body to embrace substantially the entire upper portion of the body to thereby maintain the body in foot-receiving configuration, the stiffening members having guiding and securing tabs extending rearwardly from the body and terminating at locations within the length of the sole, and adhesive located in a small area at the rear terminal of each tab to secure the tab to the shoe.

3. A foot protector comprising a body of thin elastic non-porous material having a sole por-

tion and an upper portion shaped to substantially conform to and incase the toe area and forward portion of the foot, a plurality of non-elastic stiffening members secured to the body to embrace substantially the entire upper portion of the body, a non-elastic stiffening member secured to the body to embrace substantially the entire sole portion thereof, the stiffening members having guiding and securing tabs extending rearwardly from the body and terminating at locations within the length of the sole, and adhesive applied to a small area at the rearward terminal of each tab.

MINNIE LEVY.
